UNITED STATES PATENT OFFICE.

GEORGE E. SMITH, OF MIDDLEPORT, NEW YORK.

HOOP-BENDING MACHINE.

SPECIFICATION forming part of Letters Patent No. 289,936, dated December 11, 1883.

Application filed April 4, 1883. (No model.)

To all whom it may concern:

Be it known that I, GEORGE E. SMITH, a citizen of the United States, residing at Middleport, in the county of Niagara and State of New York, have invented certain new and useful Improvements in Hoop-Bending Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in that class of hoop-bending machines wherein an endless belt passes around a system of rollers and bears against a revolving drum, around which the hoop-poles are coiled by passing between the tight belt and the face of the drum.

The object of the invention is to provide a more economical and efficient means of varying the tension of the belt accordingly as a greater or lesser number of hoop-poles are passed and carried between the drum and belt at a single operation.

In considering the present state of the art especial reference is made to the Letters Patent issued to myself on the 12th day of October, A. D. 1869, and numbered 95,845.

In the accompanying drawings, Figure 1 is a side and Fig. 2 a rear perspective view of a hoop-bending machine of the class above described with my improvements incorporated therein, like letters referring to like parts in the two views.

A A represent the two sides of the frame of the machine; B the upper cross-bar, and C the lower cross-bar, of the frame.

D D represent two rollers, suitably journaled in the frame, and E a larger roller or drum, around which the hoop-poles are passed in the process of coiling or bending.

I is the endless belt, which passes around the rollers D D, and also the tension-roller F, and bears against the drum E, so as to supply the pressure needed for the bending of the hoops.

G G are bow-springs, with re-enforces g g. Each spring is curved inwardly at its lower

end to form an eye, through which passes the bolt k, whereby each spring is secured between the arms of the slide K. This slide has a longitudinal slot, k', by means of which the slide is held in place with its arms at a greater or lesser distance from the edge of the upright A when clamped by a bolt, k'', coming through from the upright, and provided with a screw-nut and washer. The upper end of each spring is twice bent at a right angle, once outwardly and once downwardly, so as to give strength and finish to the end. Threaded eyes g' g' are provided for the reception of a hand-screw, H, which bears against the base of a recess or chamber, a', formed in the edge of the upright A, the edge being there made broad to afford room for the chamber. By turning the hand-screw to the right the end of the spring is made to set out from the edge of the upright for the purpose of increasing the tension upon the band I.

Journal-boxes f f are formed upon the outer surface of the re-enforces g g, for the purpose of carrying the tension-roller F.

Having thus described my invention, what I claim as new and useful, and desire to secure by Letters Patent, is—

1. In hoop-bending machines, the herein-described pair of bow-shaped springs, located one at each end of the tension-roller, and supporting the same by a collar attached to the center and front of each spring and slipped upon the axle of said roller, the ends of each spring adjustably bearing against the edge of the adjacent upright post near the head and the foot of said post, for the purpose of regulating the tension of the endless belt by whose pressure and curvilinear motion the hoops are bent.

2. In hoop-bending machines, the combination consisting of the herein-described bow-shaped springs carrying the tension-roller and bearing against the upright posts, the herein-described collars by which the tension-roller is supported and kept in place, the herein-described re-enforces attached to the front faces of the bow-shaped springs, the herein-described slides working upon the outer faces of the upright posts to regulate the distance between the drum or middle roller and the tension-roller, the herein-described slots cut

horizontally in the faces of the upright posts to permit the drum to be carried toward or from the tension-roller, the herein-described hand-screws bearing against the upright posts 5 and working through the upper ends of the bow-shaped springs, the herein-described chambers or recesses formed in the upper part of the edges of the upright posts, to receive the hand-screws by which the upper ends of the 10 bow-springs are retained and adjusted, and the herein-described journal-boxes formed

upon one end of the horizontal slides which work upon the upright posts, for the purpose of regulating the tension of the endless belt by which the bending of hoops is effected. 15
In testimony whereof I affix my signature in presence of two witnesses.

GEO. E. SMITH.
